UNITED STATES PATENT OFFICE.

PAUL I. BURKS, OF LOUISVILLE, KENTUCKY.

FOUR-WAY VACUUM-PUMP.

1,219,242.

Specification of Letters Patent. Patented Mar. 13, 1917.

Application filed April 19, 1915. Serial No. 22,376.

To all whom it may concern:

Be it known that I, PAUL I. BURKS, a citizen of the United States, residing at Louisville, in the county of Jefferson and State 5 of Kentucky, have invented new and useful Improvements in Four-Way Vacuum-Pumps, of which the following is a specification.

This invention relates to pneumatic piano 10 player mechanism, and has particular reference to an improved vacuum pump for controlling the exhaust chamber of the mechanism.

An object of this invention is to provide 15 a pump which produces practically a continuous suction upon the exhaust chamber, and to provide the pump with a novel automatic flushing means controllable from the tracker bar.

20 Another object of this invention is to provide a vacuum pump with a flushing valve at one side thereof, and a pneumatic on the pump communicating therewith and having connection with the flushing valve, and to 25 provide a valve between the pneumatic and the pump controlled from the tracker bar for establishing communication between the pneumatic and the pump to open the flushing valve, or between the pneumatic and the 30 outside atmosphere to close the flushing valve.

The above and other objects and advantages of this invention will more particularly appear from the following detail description of the present embodiment of the invention, the same being illustrated in the accompanying drawings wherein,—

Figure 1 is a side elevation of the improved vacuum pump.

40 Fig. 2 is a longitudinal vertical section taken through the pump, parts of the same being shown in elevation.

Fig. 3 is a section taken on the line 3—3 of Fig. 1 showing the controlling means for 45 the flushing valve.

Fig. 4 is a vertical transverse section of the pump on the line 4—4 of Fig. 2, looking toward the central portion of the pump.

Referring to these drawings wherein like 50 parts are designated by similar characters of reference throughout the several views, 10 designates the frame or casing of the pump which is rectangular in cross-section, and which is provided with a main channel 11 55 extending entirely around the casing and having an opening 12 adapted for connec-

tion with the exhaust chamber of a pneumatic player mechanism.

Within the casing 10, and at each side thereof is secured a bellows, the base 13 of 60 which is provided with an opening 14 communicating with the main channel 11 in the casing. The base 13 is provided with a flap valve 15 controlling the opening 14 to prevent the inflow of air to the main channel 11. 65 The movable section or leaf 16 of the bellows is preferably provided with a plurality of openings 17 through which air is adapted to be expelled upon the collapsing of the bellows, and which are adapted to be closed by 70 a flap valve 18 secured to the outer side of the leaf 16 and adapted to automatically close on the expansion of the bellows. The frame 10 is thus provided with four bellows 75 of this type.

A crank shaft 19 is mounted in the middle of the frame 10 upon brackets 20 and has its crank portion connected to the movable sections 16 of the bellows by means of connecting rods 21. The connecting rods 21 80 may be of any suitable and adaptable form, the same in the present instance being disclosed as comprising split bars having sockets or recesses in their opposite ends for the reception of the crank portion of the shaft 85 19 and pins 22 respectively. The pins 22 are carried upon the movable sections 16 of the bellows. The rods 21 are tightened upon the crank shaft and the pins 22 by means of suitable set-screws 23, by means of which 90 the clamping action may be adjusted. As shown in Fig. 1, the crank shaft 19 is provided with a suitable drive wheel 24 adapted to receive a belt or the like from a suitable motor for driving the vacuum pump. 95

The casing 10 is provided at one side, the upper side being shown in the present instance, with a flushing opening 25 communicating directly with the main channel 11. A flushing valve 26 is hinged upon the side 100 of the casing 10 and adapted to close the opening 25. The improved means for operating the flushing valve 26 to open and close the main channel 11 is shown in the present instance as comprising a block made 105 up of four sections 27, 28, 29 and 30. This block is located adjacent to the flushing valve 26 and supports a pneumatic 31, the movable section of which has secured thereto an arm 32 connected by a pin 33 to the 110 flushing valve 26. From Figs. 1 and 2 it will be readily seen that when the pneumatic

31 is collapsed the flushing valve 26 is open and when the pneumatic 31 is expanded the flushing valve 26 is closed.

The section 27 of the block is provided upon its inner side with a recess extending substantially the entire length of the block and providing a suction chamber 34 communicating by a passage 35 with the main channel 11 of the pump. The section 28 of the block is provided near one end with a recess 10 closed at its open side by a diaphragm 36 forming an air receiving chamber 37 in the block 28. The block 28 has a bleed opening 38 leading from the chamber 37 to the exhaust chamber 34. A tube 39 leads from the chamber 37 to the tracker bar and is adapted to be closed upon the passage of the note sheet from the tracker bar, and to be opened as the note sheet has completed its playing operation.

20 The diaphragm 36 is provided with a stem 40 extending through the sections 29 and 30 and having its outer end supported in a suitable bracket 41 secured to the section 30. 25 The section 29 is provided with a suction chamber 42 opposite to the diaphragm 36, the suction chamber 42 extending laterally beyond the diaphragm and communicating through an opening 43 in the block 28 with the exhaust chamber 34. The block 29 is 30 provided in its opposite side with a valve chamber 44 communicating with the bellows 31 and containing a disk valve 45 adapted to close the opposite sides of the valve chamber so as to cut off communication of the pneumatic 31 with the main channel 11 of the vacuum pump or the outside atmosphere through the section 30 as desired.

In operation the crank shaft 19 is rotated 40 in any suitable manner, and the bellows of the pump frame 10 consecutively draw the air from the main channel 11 and, as the main channel 11 is in communication through the opening 12 with the exhaust 45 chamber of the player mechanism, the pump creates a suction from the exhaust chamber. This action takes place when the note-sheet closes the opening in the tracker bar to which the tube 39 is connected, so that 50 air cannot enter the tube or the chamber 37 and the pump exhausts the air from the chamber 37 through the bleed opening 38. As there is thus a suction in the chamber 37, the diaphragm 36 is collapsed and draws 55 therewith the rod 40 to move the valve 45 into position to close communication between the pneumatic 31 and the main channel 11. At the same time the valve 45 opens the passage from the pneumatic 31 to the 60 outside atmosphere through the section 30. The flushing valve 26 is therefore permitted to close the flushing opening 25 so that the pump must operate upon the exhaust chamber to draw the air therefrom.

65 When the note sheet has entirely passed

over the tracker bar the pipe 39 is opened and air is permitted to pass through the pipe 39 into the chamber 37. As the chamber 42 at the opposite side of the diaphragm 36 is in communication with the pump the diaphragm is immediately distended and moves the rod 40 and its valve 41 into the opposite position to close communication between the outside atmosphere and the bellows 31, and to establish communication between the bellows and the pump. When the valve is in this position the pump exhausts the bellows and collapses the same so as to move the flushing valve outwardly from the opening 25 and thus flush the main channel 11. By this arrangement of parts the flushing valve is in communication directly with the pump, and the means for operating the flushing valve is immediately adjacent the same, so that the parts will respond quickly to the action of the note sheet so as to prevent the playing of the mechanism after the note-sheet has left the tracker.

What is claimed is—

1. In pneumatic player mechanism the combination with a vacuum pump adapted for connection with the exhaust chamber of the mechanism and a tracker-bar, of a flushing valve for the pump, and operating means for the flushing valve to open and close the same controlled directly from the tracker bar of the mechanism.

2. In pneumatic piano player mechanism, the combination with a vacuum pump and a tracker-bar, of a flushing valve communicating directly with the pump, a pneumatic connected to the flushing valve, and a valve on the pneumatic connected to the tracker-bar and adapted to establish communication between the pneumatic and the pump for opening the flushing valve and to establish communication between the pneumatic and the atmosphere whereby to close the flushing valve.

3. In pneumatic piano player mechanism, the combination with a vacuum pump and a tracker-bar, of a flushing valve communicating directly with the pump, a pneumatic connected to the flushing valve, and means actuated from the tracker-bar connected to the pneumatic and the pump and adapted to be operated to establish communication between the pneumatic and the pump whereby to open the flushing valve and adapted to be operated to establish communication between the pneumatic and the atmosphere whereby to permit the closing of the flushing valve.

4. In pneumatic piano player mechanism, the combination with a vacuum pump and a tracker-bar, of a flushing valve on the pump and means controlled from the tracker-bar for opening the flushing valve by the suction of the pump.

5. In pneumatic piano player mechanism

the combination with a vacuum pump and a tracker-bar, of a flushing valve for the pump, a pneumatic connected to the valve, and means for the pneumatic controlled from the

5 tracker-bar to place the pneumatic in communication with the pump to collapse the pneumatic and open the flushing valve.

6. In pneumatic piano player mechanism and in combination, a vacuum pump, a flushing valve for the pump, a pneumatic connected to the flushing valve, a block supporting the pneumatic and having a chamber therein communicating with the pump, a diaphragm in said chamber dividing the 15 same, a tracker bar controlled tube leading from one side of the diaphragm, a valve connected to the diaphragm adapted to control communication between the pneumatic and the pump, said diaphragm being adapted to 20 vibrate whereby to open and close said valve with respect to the passage between the pneumatic and the pump.

7. In pneumatic piano player mechanism and in combination, a vacuum pump, a flushing valve on one side of said pump, a pneumatic connected to the valve, a block supporting the pneumatic and having a chamber therein communicating with the pump and having a flushing chamber therein, a 25 diaphragm between said chambers in the block, and a valve in the block having connection with said diaphragm adapted to be moved thereby to open communication be-

tween the pneumatic and the pump whereby said pump is adapted to exhaust said pneumatic and collapse the same to open the flushing valve.

8. A vacuum pump comprising a casing having a channel therein, means for creating suction in said channel, and a flushing valve 35 on said casing communicating with said channel and adapted to be opened by the suction in the channel, pneumatic means for opening and closing said flushing valve, actuating means for said pneumatic means, and 40 means independent of said suction-creating means for controlling said actuating means.

9. In a pneumatic piano player mechanism, the combination with a vacuum pump, of a flushing valve communicating directly 45 with the pump, a pneumatic connected to the flushing valve, and a second valve on the pneumatic adapted to establish communication between the pneumatic and the pump for opening the flushing valve, and to establish communication between the pneumatic and the atmosphere to close the flushing valve, and means independent of said vacuum pump for actuating said second valve.

In testimony whereof I have hereunto set 50 my hand in presence of two subscribing witnesses.
